UNITED STATES PATENT OFFICE

1,935,918

LOADING COIL CONTAINER

Cecil Rhodes, Southport, and John Hay Phillips,
Liverpool, England, assignors to Associated
Telephone and Telegraph Company, Chicago,
Ill., a corporation of Delaware

Application January 27, 1932, Serial No. 589,119,
and in Great Britain January 30, 1931

11 Claims. (Cl. 178—46)

The present invention relates to loading coils for telephone lines and more particularly concerns improvements in their method of mounting. Hitherto it has been usual to mount the coils in groups on wooden spindles in such manner that each coil is shielded from its neighbour by a metal washer of slightly larger diameter than the coil, while moreover metal screens are employed to effect shielding between adjacent groups of coils. Although such arrangements have already been widely used and have achieved a considerable amount of success in operation the mounting of the coils on a common spindle is not altogether desirable since with this arrangement the lower coils are required to withstand the weight of those above, and this may be considerable in the case of large groups, while moreover the replacement of a coil which may have become defective during assembly is rendered extremely difficult owing to the presence of the centre mounting spindle.

The object of the present invention therefore, is to overcome these disadvantages by an improved method of mounting and according to one feature of the invention therefore each loading coil is located in a separate tube, the ends of said tubes being closed flat plates which are clamped in position by a fixing means common to a number of said tubes.

According to a further feature of the invention a mounting arrangement for a loading coil comprises a tube of internal dimensions substantially the same as those of the loading coil, the ends of said tube being closed by flat plates.

The invention will be better understood from the following description of one method of carrying it into effect reference being had to the accompanying drawings comprising Figs. 1, 2 and 3 which show in detail the screening arrangements for a particular coil, while Figs. 4 and 5 show a number of coils assembled in column to a common fixing means.

Referring now particularly to Fig. 1, this shows a plan view of the tube 10 preferably composed of metal of high electrical conductivity, provided with the insulating bushes 11 set diametrically opposite to each other through which connection to the coils may be made. Fig. 3 shows a typical flat plate 12 also composed of metal of high electrical conductivity provided with the lugs 13 which are drilled to accommodate the common fixing means. In order to provide a locating means for the tubes 10 the tongues 14 are pressed up out of the plate 12 in circle substantially equal to the inside diameter of the

tube. Fig. 2 shows in section the screening arrangements for a single coil from which it will be seen that the tube 10 is located over the projections 14 in the lower plate 12 while the upper plate 16 which closes the upper end of the tube 60 is also provided with projections 17 for locating the tube of the adjacent assembly. With this arrangement it will be seen that a single flat plate is employed for closing the ends of adjacent tubes. When mounted in position the plates and 65 tubes are clamped tightly together so that good electrical connection will be established between the components.

Preferably also the container so formed will have its inner faces adjacent to the coil, lined 70 with an insulating material, and this is accomplished by providing the insulating discs 18 and 19 above and below the coil while the outer edges of the coil are encircled by a flexible strip of insulating material 20.

In this manner the coils are insulated and completely surrounded by metal of high conductivity and are by this means rendered almost immune from cross talk due to electromagnetic induction.

Referring now particularly to Fig. 4 which shows the coils assembled in their mounted position, it will be assumed for the purpose of this description that the upper mounting platform 21 is the lid of a loading coil container of the generally accepted design. To this platform are screwed or welded four supporting rods 22 threaded at their ends and provided with the nuts 23 by means of which the assembly may be clamped in position. The method of assembly is such that the plates and tubes which contain the coils are alternately mounted and when the full capacity of the rods is reached the columns so formed are clamped in position by the nuts previously mentioned. Conveniently also the centre 90 two supporting rods are used in common by the outer and middle columns and it will be realized that this method of mounting will present little difficulty providing that the sequence of mounting shown in the drawings is observed.

Should now a coil have become defective during assembly this may be readily removed and replaced by slackening off the clamping nuts of the associated supporting rods and prising the metal tube over the projections on the plate so 105 that the tube and coil may be withdrawn sideways from the column. In practice of course, it will generally be found necessary when the coil and tube are removed for a suitable block of wood or like material to be inserted between the upper 110

and lower plates so as to prevent displacement of the whole assembly. A further advantage may be found in the fact that since the coil assemblies are in effect hinged to the supporting rods 5 they may be collapsed towards each other in the manner indicated in Fig. 5 so as to economize in the overall mounting space.

What we claim as new and desire to secure by Letters Patent is:

10. 1. In a mounting arrangement for loading coils, a plurality of tubes, plates closing the ends of said tubes, a loading coil located in each of said tubes, and fixing means common to said tubes and extending through said plate outside 15 of said tubes for clamping said plates and tubes in position.
2. In a mounting arrangement for loading coils comprising a tube having internal dimensions substantially the same as those of a loading coil, flat plates closing the ends of said tube and forming the sole support for the loading coil, and means extending through said plates outside of said tube for clamping said plates in position.
25. 3. In a mounting arrangement for loading coils, a plurality of tubes mounted in column formation, a loading coil in each of said tubes, flat plates between each of said tubes, and locating projections on said flat plates engaging 30 with said tubes so as to maintain them substantially concentric with one another.
4. In a mounting arrangement for loading coils, a plurality of tubes mounted in column formation, a loading coil in each of said tubes, flat plates between said tubes and closing the 35 ends thereof, and a plurality of projecting lugs formed out of said flat plates in a circle substantially equal to the inside diameter of said tubes to maintain them concentric with one another in the column.
45. 5. In a mounting arrangement for loading coils, a plurality of tubes arranged in column formation, a loading coil in each of said tubes, flat plates between said tubes and closing each 50 end thereof, lugs on said flat plates, and common fixing means extending through said lugs for clamping said plates and tubes together.
5. In a mounting arrangement for loading coils, a plurality of tubes arranged in column formation, a loading coil in each of said tubes, flat plates between each tube and closing its ends, 55 lugs on said flat plates, and common fixing rods extending through said lugs for clamping said flat plates and tubes together, said fixing rods arranged in staggered formation with respect to one another.
7. In a mounting arrangement for loading coils, a plurality of rows of tubes, the tubes in each row arranged in column formation, a load-

ing coil in each of said tubes, flat plates between each of said tubes and closing the ends thereof, lugs on said flat plates, supporting rods common to each row of tubes and extending through said lugs for clamping said tubes and plates together, 80 said supporting rods arranged in staggered formation with respect to one another and the rows of tubes.

8. In a mounting arrangement for loading coils, a plurality of tubes arranged in column formation, a loading coil in each of said tubes, flat plates between said tubes and closing the ends thereof, projecting lugs formed in said plates and engaging said tubes to support them concentric with one another, means for clamping said plates and tubes together, said clamping means arranged to be loosened slightly to permit withdrawal of any one of said tubes and its associated loading coil from between said flat plates without disturbing the other tubes and loading 90 coils in the column.

9. In a mounting arrangement for loading coils, a plurality of tubes arranged in column formation, a loading coil in each of said tubes, flat plates separating said tubes and closing the 100 ends thereof, projecting lugs concentrically spaced on said plates and engaging the side of said tubes to support them one above the other, supporting rods engaging said plates outside of said tubes to clamp said plates and tubes together, said supporting rods arranged to be loosened slightly to separate any pair of plates and disengage the projecting lugs from a tube to permit it to be removed together with its associated coil without disturbing the remaining tubes 105 and loading coils in the column.

10. In a mounting arrangement for loading coils, a plurality of tubes arranged in column formation, a loading coil in each of said tubes, flat plates between each tube and closing the ends 115 thereof, said plates and said tubes forming the sole support for the loading coils, and means for clamping said plates and tubes together so as to permit the removal of any loading coil without disturbing the remaining ones in the column.

11. A mounting arrangement for loading coils comprising separate tubes mounted in a column and each containing a loading coil, flat plates separating and closing the ends of each tube, said tubes and said flat plates forming the sole support for said loading coils, means for clamping said plates and tubes together, said clamping means arranged to permit the removal of a single tube and its associated loading coil from the column while maintaining the remaining ones 125 intact.
